UNITED STATES PATENT OFFICE.

CHARLES K. WOODIN, GEORGE E. KARL, AND JOHN F. KOLCZYNKI, OF BEREAL, OHIO,
ASSIGNORS TO THE DUNHAM COMPANY, OF BEREAL, OHIO, A CORPORATION OF OHIO.

APPARATUS FOR FORMING CAST-METAL WHEELS.

1,858,911.

Specification of Letters Patent.

Patented Nov. 16, 1920.

Original application filed December 26, 1918, Serial No. 268,386. Divided and this application filed February 14, 1919. Serial No. 277,078.

To all whom it may concern:

Be it known that we, CHARLES K. WOODIN, GEORGE E. KARL, and JOHN F. KOLCZYNKI, citizens of the United States, residents of Berea, county of Cuyahoga, and State of Ohio, have invented new and useful Improvements in Apparatus for Forming Cast-Metal Wheels, of which the following is a specification, the principle of the invention being herein explained and the best mode in which we have contemplated applying that principle, so as to distinguish it from other inventions.

Our invention relates to apparatus for forming hollow cast metal wheels having a rim, the outer portion of which is chilled and the inner portion of a softer nature, whereby to form a strengthening backing for the chilled portion; and more particularly in forming such wheels for use in agricultural implements adapted for pulverizing or mulching the soil.

Wheels of the above described character when intended for agricultural purposes depend for their effectiveness upon the concentration of the weight of the machine upon hard lumps in order that such lumps may be cut, broken and cracked so that the further action of the wheels in rolling over the pieces may properly pulverize them. Furthermore, we have found that such effectiveness is enhanced by providing the wheel with a sharp cutting edge and with a hard exterior smooth surface that will resist a tendency of the moist earth to stick thereto.

Heretofore agricultural wheels have been cast of ordinary gray iron but it was found that the desired sharpness of the edge of the above mentioned annular apex portion could not be retained, by reason of the character of the gray iron which, as is well known, is comparatively soft and quickly wears out. Furthermore, in the casting operation it was found impractical to provide an initially sharp edge for the reason that these wheels have always been cast in sand molds and, as is well known, a well defined, sharp, thin structure is difficult to obtain by these means. Furthermore, these gray iron wheels have a rough exterior surface to which the moist earth adhered readily and thus impeded the ready movement of the implement over the

ground, as well as interfering with the proper mulching or pulverizing of the soil. Such rough exterior surface, furthermore, required an excessive amount of paint or pigment which is usually applied thereto after the manufacturing is complete and before shipping to the user.

In addition, it has been found necessary to reduce the cost of the production of these wheels, inasmuch as a soil pulverizer includes in its structure a great number thereof and the labor in producing wheels of this character is now a limiting factor in the production of soil pulverizers. Furthermore, the price at which soil pulverizers must be sold at the present time prohibits the improvement of the wheels by methods which would increase the cost.

To this end we have provided a metal mold (preferably cast iron), upon the interior of which is suitably supported, as will be hereinafter more fully explained, a porous sand core, the mold and core together forming an interior space into which the metal is poured to form the required wheel. As is well known, certain kinds of molten mixtures of iron, cast into a metal mold and coming into contact with the metal, chills to form what is known as white iron. Such chilling takes place in our improved process, but the sand core, being of markedly less heat conductivity, does not cause the iron which comes into contact with it to become chilled, with the result that we obtain a wheel, the rim portion of which in particular has its outer or superficial structure of white iron and its inner structure of gray iron. The white iron, as is well known, is of glass-like consistency and extremely brittle, having small resistance to flexure. The gray iron on the other hand is comparatively tough, and embodies those characteristics necessary to give the rim portion of the wheel the required strength.

We have found that by utilizing a certain type of mold and limiting the time in which the wheels are permitted to remain in the mold to a predetermined period, we have been able to control the amount of chilling action which takes place so as to provide these comparatively thin structures with the required exterior white iron structure and

the interior gray iron structure, thus enabling us to utilize the advantageous characteristics of such white iron exterior surface and to obtain the required sharp apex portion of the wheel and to produce the entire wheel at a comparatively low cost, while having the necessary characteristics of strength.

Reference is had to our copending application, Serial No. 263,386, which discloses and claims the wheel and the method of making the same.

Among the objects of our invention, therefore, is to provide an apparatus for forming hollow cast metal wheels having a rim portion, the outer face of which is chilled and the inner portion of which rim is unchilled and of a softer nature to act as a strengthening backing for the chilled face; further to provide an apparatus for accomplishing the maximum output of such wheels with a minimum expenditure of time, labor and expense; further to make possible the manufacture of such a hollow cast metal wheel of maximum simplicity and efficiency; further to make possible the production of a wheel for agricultural purposes having a chilled outer face with a sharp cutting edge and light in weight without sacrificing its strength; further to provide such apparatus that can be readily and quickly operated whereby to control the depth of chill and insure a good casting; and such further objects, advantages and capabilities as will later more fully appear.

Our invention further resides in the combination, construction and arrangement of parts illustrated in the accompanying drawings, and while we have shown therein a preferred embodiment, we desire it to be understood that the same is susceptible of modification and change without departing from the spirit of our invention.

In said annexed drawings:

Fig. 1 represents a side elevation of a mold utilized in carrying out our present invention.

Fig. 2 represents a top plan of such mold.

Fig. 3 represents the mold when open and showing a casting therein just prior to its removal, the cope of the mold being shown in axial section.

Fig. 4 represents a bottom plan of the cope of the mold taken upon the plane indicated by line IV—IV, in Fig. 1 and viewed as indicated by the upwardly extending arrows.

Fig. 5 represents a top plan of the drag of the mold upon the plane indicated by line V—V, Fig. 1, and as indicated by the downwardly extending arrows.

Fig. 6 represents a perspective of the sprue core.

Fig. 7 represents an axial section, upon an enlarged scale, of the drag and cope of

the mold closed and showing the position which it occupies just prior to the casting operation.

Fig. 8 represents upon an enlarged scale a fragmentary axial section of one of the resultant pulverizer wheels, such section being specifically designed to illustrate the structure of the rim portion thereof.

Fig. 9 represents a side elevation of a complete wheel, and Fig. 10 a front elevation thereof.

Fig. 11 represents an axial section of a completed wheel.

The illustrated form of mold comprises a cast iron drag 1 and a cast iron cope 2 which are pivotally connected by means of a pin 3, Fig. 1. The outer end of the drag is provided with a lug 4 having a conical recess 5 which receives the conical lower end of a pin 7 fixed to a lug 8 projecting from the front of the outer swinging end of the cope. The function of this pin and recess is to permit the proper registration of the cope and drag and their retention in a fixed position laterally during the casting operation, as will be readily understood.

Pivoted upon opposite sides, respectively, of the drag are two latches 9 which are adapted to engage a lug 10 whereby the cope and drag may be locked together.

The drag is formed with the inner central recess 11, the middle portion 12 of which extends downwardly and pierces the lower surface of the drag. This recess 11 determines the exterior surface of one half of the required wheel. The complementary recess 13 in the cope determines the outer surface of the other half of the wheel and an upwardly extending cylindrical and centrally located recess 14 is provided. The form of the recesses 11 and 13 is such as will produce an outer surface of a wheel such as illustrated in Figs. 9 to 11, inclusive.

For the purpose of determining the inner surface of the wheel, a two-part sand core 15, Fig. 7, is provided, the two parts being respectively provided with dowels 16 and recesses 17 in order to provide for their proper registration. The two parts of the core are hollowed so that when they are joined they form an interior gas receiving recess or chamber 18. The central part of the lower core parts is provided with a gas duct 20. These bosses are made slightly tapered, as shown, and are adapted to fit in the recesses 12 and 14, whereby the core is centered. The diameters of these bosses 19 are such that they will cause the core to assume a position in which its outer surfaces are removed from the inner surface of the mold, as shown in said Fig. 7 and these inner surfaces are so designed that they will produce a rim portion of the wheel which is of maximum thickness at the lateral portions thereof and of minimum thickness near the

central or apex portion of such wheel, as illustrated in Fig. 8, and as will be understood, suitable grooves are provided in the drag and cope for the formation of the spokes of the wheel.

The cope comprises in its structure an upwardly displaceable steel member or insert 21, which is generally cylindrical in form and whose lower portion is tapered as 16 at 22. This tapered portion fits into a tapered conical aperture 23 and the lower surface of the member 21 determines the upper surface of the casting and contains the cylindrical recess 14. One side of the member 21 is provided with a tapered recess 24 which receives the sprue core 25 having the tapered opening 26 and also lateral ducts 27 extending both ways from the central opening 26, as shown in Fig. 6.

20 To the upper end of the member 21 is secured an upright 28 having an elongated slot 29, through which extends a bolt 30. This bolt passes through and is secured to a lever 31 pivoted at 32 to an upright 33 fixed 25 to and forming a part of the frame and mold. The bolt 30 is so arranged that it extends loosely through the slot 29 so that the member 21 may move upwardly.

Pivottally mounted upon the lever 31 is a 30 latch 34 which is adapted to swing free and engage the sprue core 25, whereby the latter is held in position during the pouring operation. This lever 31 is furthermore offset, as shown in Fig. 2, so as to avoid being in 35 a position directly above the sprue core, thus allowing ready access to the latter. A weight 35 is secured to the outer end of the lever 31 which provides sufficient resistance to the displacement of the sprue core 35 40 when the latch 34 is in its locking position.

Secured to the standard or upright 33 and adjacent to the pivot 32 is a stop 36 inclined upwardly, as shown. Fixed to the front of the cope 2 is a horizontally extending 45 bar 37 to which may be applied a pipe for the purpose of forming a lever or handle adapted to lift the cope, as will be herein-after described.

The mold being in the position shown in 50 Fig. 1, it is ready for the casting operation. Any suitable mixture that will produce, when chilled, a white iron, may be used. We have found that one mixture for this purpose comprises iron having 2.5% of 55 silicon, 10% sulfur, .30% to .50% of phosphorus and .50% to .80% of manganese. These proportions may, of course, be varied, the amount of chill to be obtained being primarily determined by the proportion of silicon and manganese used.

This molten mixture is now poured into the mold through the sprue core and flows rapidly around in both directions and fills the space between the mold and the core. 65 As soon as the mold is filled, the pipe is

applied to the bar 37, the latches 9 are disengaged from the lugs 10 and the cope is lifted upwardly and swung over into the position shown in Fig. 3. This action automatically disengages the stop 34 from the 70 sprue core and the momentum of the weight 35 carries the lever 31 backwardly until it strikes the stop 36. This action disengages the displaceable cope member 21 and removes it from the recess 23, as shown in said 75 figure. The sprue core is now knocked off, after which it will be seen that the casting is free to be removed from the mold. This is done quickly.

This described operation results in the arrest of the chill which takes place as soon as the molten metal strikes the cold interior surface of the iron mold and a rim portion structure is obtained such as is illustrated in Fig. 8, in which the outer portion 38 of 85 the metal is chilled and the inner portion 39 consists of gray iron.

It will be observed from this figure that the cross-section of this rim portion consists of two similar legs angularly related 90 and having outer and inner outwardly converging surfaces forming an apex portion 40. These legs, as a result of the previously described design of mold and core, are of a minimum thickness near the apex portion 95 and of a maximum thickness at the lateral portion of these legs. As a result of this form of section, the apex portion and the leg portions of minimum thickness become substantially chilled throughout their entire 100 structure and this chilled zone decreases in thickness laterally, as shown, until it reaches a minimum near the extreme lateral portions of the legs. Conversely, the gray iron portion 39 increases in thickness laterally. 105 As a result, the gray iron is distributed in the most advantageous manner, inasmuch as the thickest portion of such gray iron is located at that part of the structure which is subjected to the greatest amount of flexural 110 stress. In addition a smooth exterior surface is obtained and a sharp point at the apex portion, all of which, as was previously described, is desirable and contributes to the 115 economical operation and functioning of the wheel.

While we have illustrated and described our apparatus in connection with the manufacture of wheels adapted for use in agricultural implements, it is, of course, obvious 120 that other shapes and styles of wheels for other purposes may be made without departing from the spirit of our invention.

Having now described our invention, we claim:

1. An apparatus for casting hollow metal wheels, a permanent metal mold designed to form the exterior surface of said wheels, said mold having in its upper part a displaceable metal insert whose lower face forms 125

part of the mold surface, and a two part hollow core of markedly less heat conductivity and of a size and shape to form with said permanent mold a comparatively thin space whereby to provide a rim having a chilled outer face and an unchilled inner strengthening backing.

2. In apparatus for casting hollow metal wheels, a permanent metal mold for forming a chilled outer surface, and a two part hollow core of less heat conductivity than said mold and fitted in said mold to form therewith a comparatively thin space, and prevent the molten metal forming the inner portion of the wheel from chilling.

3. In apparatus of the class described, a permanent mold comprising upper and lower parts of material adapted to chill molten metal when poured thereagainst and of a shape to form the exterior surface of a desired casting, and a core of markedly less heat conductivity than said mold so arranged within said mold that when molten metal is poured into the mold the molten iron contacting the permanent mold surfaces will become chilled and very hard while that portion contacting the core will be unchilled and remain in a softer condition to act as a strengthening backing for the chilled portion.

4. In apparatus of the class described, a permanent mold comprising upper and lower parts of material adapted to chill molten metal when poured thereagainst and of a shape to form the exterior surface of a desired casting, and a core of markedly less heat conductivity than said mold so arranged within said mold that when molten metal is poured in the mold the molten iron contacting the permanent mold surfaces will become chilled and very hard while that portion contacting the core will be unchilled and remain in a softer condition to act as a strengthening backing for the chilled portion, and a displaceable metal insert for forming part of the mold surface mounted in said upper part.

5. In apparatus of the class described, a permanent mold comprising upper and lower parts of material adapted to chill molten metal when poured thereagainst and of a shape to form the exterior surface of a desired casting, and a core of markedly less heat conductivity than said mold so arranged within said mold that when molten metal is poured in the mold the molten iron contacting the permanent mold surfaces will become chilled and very hard while that portion contacting the core will be unchilled and remain in a softer condition to act as a strengthening backing for the chilled portion, said upper and lower parts being hinged together, whereby the mold may be quickly opened and closed.

6. In apparatus of the class described, a

mold comprising an upper and lower part having interior faces adapted to chill the molten metal when poured into contact therewith, said upper and lower parts being hinged together, and said upper part having a displaceable metal insert whose lower face is adapted to form part of the mold, said insert being yieldingly held in position whereby strains and expansion set up within the mold will be automatically relieved.

7. In apparatus of the class described, a mold comprising an upper and lower part having interior faces adapted to chill the molten metal when poured into contact therewith, said upper and lower parts being hinged together, and said upper part having a displaceable metal insert whose lower face is adapted to form part of the mold, said insert having an opening therethrough adapted to receive a sprue core.

8. In apparatus of the class described, a mold comprising an upper and lower part having interior faces adapted to chill the molten metal when poured into contact therewith, said upper and lower parts being hinged together, said upper part having a displaceable metal insert whose lower face is adapted to form part of the mold, said insert having an opening therethrough adapted to receive a sprue core, and means for holding said sprue core in position while pouring.

9. In apparatus of the class described, a mold comprising an upper and lower part having interior faces adapted to chill the molten metal when poured into contact therewith, said upper and lower parts being hinged together, said upper part having a displaceable metal insert whose lower face is adapted to form part of the mold, said insert having an opening therethrough adapted to receive a sprue core, and means for holding said sprue core in position while pouring, said means comprising a weight operated latch.

10. In apparatus of the class described, a mold comprising an upper and lower part having interior faces adapted to chill the molten metal when poured into contact therewith, said upper and lower parts being hinged together, and said upper part having a displaceable metal insert whose lower face is adapted to form part of the mold, an arm pivotally connected with said upper part and carrying a weight adjacent its outer end, said arm having connection with said insert to automatically displace the same from said upper part when opening said mold but to be loosely connected therewith when said mold is closed.

11. In apparatus of the class described, a mold comprising an upper and lower part having interior faces adapted to chill the molten metal when poured into contact therewith, said upper and lower parts being hinged together, and said upper part having

- a displaceable metal insert whose lower face is adapted to form part of the mold, an arm pivotally connected with said upper part and carrying a weight adjacent its outer end, said arm having connection with said insert to automatically displace the same from said upper part when opening said mold but to be loosely connected therewith when said mold is closed, a sprue core inserted through said displaceable insert, and a latch pivotally carried by said arm and adapted to be held against said sprue core by said weight when the mold is closed.
12. In apparatus of the class described, a mold comprising an upper and lower part having interior faces adapted to chill the molten metal when poured into contact therewith, said upper and lower parts being hinged together, and said upper part having a displaceable metal insert whose lower face is adapted to form part of the mold, an arm pivotally connected with said upper part and carrying a weight adjacent its outer end, said arm having connection with said insert to automatically displace the same from said upper part when opening said mold but to be loosely connected therewith when said mold is closed, a sprue core inserted through said displaceable insert, a latch pivotally carried by said arm and adapted to be held against said sprue core by said weight when the mold is closed, and a stop for limiting the outward movement of said arm when said mold is opened.
13. In apparatus of the class described, a mold comprising an upper and lower part having interior faces adapted to chill the molten metal when poured into contact therewith, said upper and lower parts being hinged together, said upper part having a displaceable metal insert whose lower face is adapted to form part of the mold, and means to permit the displacement of said insert when the mold is opened but to limit the amount of such displacement.
14. In apparatus of the class described, a mold comprising upper and lower parts forming the mold cavity and adapted to chill the molten iron when contacting therewith, said parts being hinged together, a core of markedly less heat conductivity than the material of said upper and lower parts and so arranged that when poured the molten metal contacting the upper and lower
- parts will be chilled and form white iron, and that contacting the core will remain in a gray iron state to act as a backing to strengthen the chilled portion, a displaceable metal insert for said upper part, a sprue core extending through said insert, easily releasable means for clamping together said parts when closed, an arm pivotally connected with the upper part and extending thereacross, a weight on said arm, means on said arm for holding the sprue core in place, means on said arm for displacing said insert when the mold is opened but loosely connected therewith when the mold is closed, and means for limiting the pivotal movement of said arm when the top part is swung back to open position.
15. In apparatus of the class described, a permanent metal mold for forming chilled exterior surfaces of a hollow casting, a core of markedly less heat conductivity than said mold and positioned therein to form unchilled interior surfaces of said hollow casting, the upper part of said mold having an opening therethrough, adapted to receive a removable sprue core.
16. In apparatus of the class described, a permanent metal mold for forming chilled exterior surfaces of a hollow casting, a core of markedly less heat conductivity than said mold and positioned therein to form unchilled interior surfaces of said hollow casting, the upper part of said mold having an opening therethrough, adapted to receive a removable sprue core, a sprue core in said opening, and releasing means for holding said sprue core in operative position.
17. In apparatus for casting hollow metal wheels, a permanent metal mold for forming a chilled outer surface, and a two part hollow core of less heat conductivity than said mold, and fitted in said mold to form therewith a comparatively thin space, and prevent the molten metal forming the inner portion of the wheel from chilling, the mold and core being so arranged that the chilled portion will decrease in thickness from the center of the rim laterally in both directions.

Signed by us, this 25th day of January, 1919.

CHARLES K. WOODIN,
GEORGE E. KARI,
JOHN F. KOŁAKOWSKI.
